UNITED STATES PATENT OFFICE

150,293

DESIGN FOR A TOY WHISTLE

Robert Y. Grant, Jr., Townsend, Mass.

Application October 17, 1947, Serial No. 141,963

Term of patent 14 years

(Cl. D34—15)

To all whom it may concern:

Be it known that Robert Y. Grant, Jr., a citizen of the United States, residing at Townsend in the county of Middlesex and State of Massachusetts, has invented a new, original, and ornamental Design for Toy Whistle, of which the following is a specification, reference being had to the accompanying drawing, forming part thereof.

Fig. 1 is a view in rear elevation; Fig. 2 is a view similar to Fig. 1 showing the wings raised; Fig. 3 is a view in side elevation; and Fig. 4 is a view similar to Fig. 3 with the wings raised, all showing my new design.

I claim:

The ornamental design for a toy whistle, as shown.

ROBERT Y. GRANT, JR.
